CONTROL MECHANISM FOR RAIL SANDERS

Henry Norton Sudduth, Watertown, N. Y., assignor to The New York Air Brake Company, a corporation of New Jersey

Application June 4, 1941, Serial No. 396,616

5 Claims. (Cl. 291—3)

This invention relates to sanding devices for railway rails and particularly to a timing valve of simple form, to time cleanout blasts.

Applicant's assignee has developed commercially certain highly organized sanding equipment intended for use on all braked trucks of high speed trains and so contrived as to be put into action by the brake system during certain types of brake application or even during all applications. Each set or group of sand traps is put into action by a piston actuated slide valve mechanism which delivers first a cleanout blast, then a sustained sanding blast through a separate connection, and finally as the device shuts down gives a final brief cleanout blast.

The general organization of the sand trap is shown in the allowed application of Charles A. Campbell, Serial No. 314,173, filed January 16, 1940, issued as Patent No. 2,243,243, May 27, 1941. These traps require the delivery of cleanout blasts through one connection and the delivery of sanding air through another.

Such traps are also desirable for single installation on the head ends of railway motor cars and on locomotives, but economy requires the use of a simple control valve of the manually operable type where the Campbell trap is so used.

The present invention attains that result by the use of simple components, many of which are standard for other uses and hence commercially available at reasonable cost. Such an embodiment of the invention will now be described.

In the drawing:

Figure 1 is a diagrammatic elevation of the manual valve, the trap, the relay and timing valve assembly, and the pipe connections.

Figure 2 is a sectional diagram on a larger scale of the apparatus shown in Figure 1, except the sand trap.

Figure 3 is a section similar to a portion of Figure 2 but showing the manual valve set in sanding position.

Referring first to Figure 1, the manual valve appears at 11 and the sand trap at 12. This is fed by a sand box 13 and delivers sand to the rail through hose 14. A pipe bracket 15 carries the relay air valve unit 16 and the timing valve unit 17, mounted on opposite sides thereof. The valve 11 is mounted in the cab and the parts 15, 16, 17 may be mounted at any convenient point.

The pipe connections are as follows: Air supply pipe 18, leading from any suitable source of compressed air, sanding actuation pipe 19, final cleanout pipe 21, sanding air pipe 22, cleanout air pipe 23.

The manual valve 11 is of the two-position rotary type. The base 24 serves as the pipe bracket, and to it are connected pipes 18, 19 and 21. The cap 25 carries the inverted seat for the rotary valve 26 which is turned by handle 27 through stem 28. As shown, there are two ports in the valve seat each communicating with a corresponding one of the pipes 19 and 21. There is also an exhaust port 29 in the seat and an exhaust loop 30 and through port 31 in the valve 26. Pipe 18 is in communication with the chamber which houses the rotary valve.

The valve has two functional positions, "running" (Figure 2) in which it vents pipe 19 and connects pipe 21 to supply, and "sanding" (Figure 3) in which it vents pipe 21 and connects pipe 19 to supply.

The bracket 15 has ports which simply form extensions of pipes 18, 19, 21, 22 and 23 and hence can be identified merely by reference to the connected pipe. Most of these have extensions in the body of relay 16, and 19 and 21 have extensions into the body of timing valve 17. These will be similarly identified. There is also an atmosphere exhaust port 32.

The sanding relay valve and the cleanout relay valve in body 16 are identical and their identical components will be identified by the same numerals distinguished by the letters *s* and *c*, so the two can be described together.

The cleanout relay comprises two reversely seated poppet valves, a supply valve 33c and a vent valve 34c. Valve 33c is held in its normal closed position by spring 35c and by supply pressure since the chamber 36c is connected with pipe 18 (as is chamber 36s of the sanding relay valve). Vent valve 34c is normally open, and when closed its pilot engages the pilot of valve 33c and holds the latter valve open. Chamber 37c between the valves is connected with cleanout air pipe 23. The corresponding chamber 37s is connected with sanding air pipe 22.

The vent valve 34c is connected by bolt 38c and thrust plate 39c with the center of actuating diaphragm 41c whose margin is clamped by a cap 42c. The space 43c above diaphragm 41c and the space 43s above diaphragm 41s are connected with exhaust port 32. The space 44c below the diaphragm 41c is connected by passage 45 with the side ports 46 of the double check valve 47. The space 44s is connected with sanding actuation pipe 19.

The timing valve unit 17 contains two identical impulse units, one operated when pressure is developed in pipe 19 to give the initial clean-

out impulse, and the other operated when pressure is developed in pipe 21 to give the final cleanout impulse. They deliver timed air surges to opposite ends of double check valve 47 so that each causes a timed surge in chamber 44c, and consequently causes timed cleanout flow through pipe 23.

The impulse unit connected with pipe 19 contains a diaphragm 51 interposed between a chamber 52 connected with pipe 19 and a closed volume 53 connected with chamber 52 by choke port 54. A spring 55 with thrust plate 56 urges diaphragm 51 toward valve seat 57 controlling flow to port 58 which leads to the right end of double check valve 47. A choke port 59 affords a restricted atmospheric vent from port 58.

The other impulse unit is identical and parts are identified by the same reference numerals increased by 100.

Operation

During running conditions, when sanding is not needed, manually operable valve 11 is in the position shown in Figure 2. Under these conditions pipe 19 is vented and pipe 21 is at supply pressure so that the chamber 153 is charged to supply pressure. Pressures on the diaphragm 151 being equal, the spring holds the diaphragm sealed against seat 157. At that time, pipe 19 and the chamber 53 are at atmospheric pressure, and similarly the diaphragm 51 is held against seat 57.

Assume now that the engineer shifts the handle 27 to sanding position establishing the conditions illustrated in Figure 3. This vents pipe 21 and charges pipe 19. The venting of pipe 21 has no immediate functional significance, but merely entails venting of chamber 153 to atmospheric pressure, the diaphragm 151 remaining seated against seat 157. But the development of pressure in pipe 19 does two things, it develops a pressure in the supply pressure chamber 44s as long as the valve remains in the position of Figure 3, and also it develops supply pressure in the chamber 52, with the result that diaphragm 51 moves to the right, since chamber 53 is initially at atmospheric pressure, and allows air to flow through port 58 against the right end of check valve 47.

The valve shifts to the left and supply pressure is developed in chamber 44c. The supply of pressure persists only until equalization of pressures through choke 54 allows the diaphragm 51 again to close against the seat 57. When this happens the choke 59 will reduce the pressure in the chamber 44c, at a rate dependent on the size of the choke.

The development of pressure in the chamber 44s develops sanding pressure in the pipe 22. So long as pressure persists in chamber 44c, cleanout flow occurs in the pipe 23. It is characteristic of the Campbell trap that if the sand hose is clogged, sand flow will not start until the hose is blown clean. Sanding will continue as long as air is delivered through the pipe 22, that is, until the valve 26 is returned to the position of Figure 2.

When this occurs pipe 19 is vented so that chamber 44s is vented, and the supply valve 33s immediately closes. However, the concurrent development of pressure in pipe 21 will develop pressure in chamber 52. The chamber 153 having been vented to atmospheric pressure, the diaphragm 151 will move to the right and supply pressure will be delivered through the valve seat 57

157 and port 158 to the left-hand end of double check valve 47. Thus, another pressure impulse is developed in chamber 44c, and there is a final cleanout blast of air through the pipe 23. This blast will be of a few seconds duration, ending when choke 159 vents chamber 44c, after closure of diaphragm 151 against seat 157.

The use of two impulse units in conjunction with the double check valve or its equivalent, affords simple means for delivering two independently timed impulses of cleanout air, one at the commencement of sanding, and the other at the termination of sanding.

While the duration of the impulse can itself have a timing effect on the cleanout blast, it is preferred to make the two impulse valves identical so that the impulses are of like duration. The timing of the cleanout blast is then controlled by determining the venting action of the chokes 59 or 159, respectively. The function of the double seated check valve 47 is to select between the chokes 59 and 159. By using the check valve and two chokes of different capacity, it is possible to have an initial cleanout blast of one duration and a final cleanout blast of different duration. Interchangeable chokes facilitate adjustment of the duration of each blast.

If difference of duration of the two cleanout blasts is not desired, the check valve 47 may be omitted. Omission of the valve 47 would place the ports 58, 158 and 45 in free communication with each other. In such case, the choke 159 can be replaced with a plug, as choke 59 would afford adequate venting.

It will be apparent therefore that the device is susceptible of considerable modification with minor resulting changes of operation. Such changes fall within the broad scope of the invention.

The arrangement illustrated is preferred for two reasons: It uses standard commercial components, some of which are identical; it permits any necessary adjustment of the duration of each cleanout blast by the simple interchange of chokes.

While the preferred embodiment has been illustrated and described in considerable detail, it is intended to be illustrative and not limiting. The scope of the invention is described in the claims.

I claim:

1. A control valve mechanism for use with sanding traps of the type having a sanding air connection and a cleanout air connection, said mechanism comprising in combination, pressure operated means for supplying sanding air to the sanding connections; two impulse valve means each effective, upon the delivery of pressure fluid thereto, to deliver a fluid pressure impulse to the cleanout connection; and a sanding control valve having a sanding position in which it supplies air under pressure to said pressure operated means and to one of said impulse valve means, and a running position in which it vents said pressure operated means and delivers air under pressure to the other of said impulse valve means.

2. A control valve mechanism for use with sanding traps of the type having a sanding air connection and a cleanout air connection, said mechanism comprising in combination, pressure operated means for supplying sanding air to the sanding connection; two distinct impulse valves each arranged to deliver a fluid pressure impulse upon the delivery of fluid pressure thereto; connections comprising check valve means and vent

chokes rendered effective selectively by the impulse valves whereby each impulse valve may deliver a characteristically timed cleanout impulse; and a sanding control valve having a sanding position in which it supplies air under pressure to said pressure operated means and to one of said impulse valves, and a running position in which it vents said pressure operated means and delivers air under pressure to the other of said impulse valves.

3. A control valve mechanism for use with sanding traps of the type having a sanding air connection and a cleanout air connection, said mechanism comprising in combination, a pressure motor actuated relay valve operable to deliver air under pressure to said sanding connection; a pressure motor actuated relay valve operable to deliver air under pressure to said cleanout connection; two impulse valves each adapted to deliver a timed pressure impulse in response to the development of pressure thereupon; a pair of vent chokes; connections comprising check valve means for connecting an active impulse valve and a corresponding one of said vent chokes with the motor of said cleanout relay; and a sanding control valve having a sanding position in which it develops pressure in the motor of the sanding relay and develops pressure on one of said impulse valves, and a running position in which it vents the last named motor and develops pressure on the other of said impulse valves.

4. A control valve mechanism for use with sanding traps of the type having a sanding air connection and a cleanout air connection, said valve mechanism comprising in combination, a pressure motor actuated relay valve operable to deliver air under pressure to said sanding con-

nection and when inactive serving to vent said connection; a pressure motor actuated relay valve operable to deliver air under pressure to said cleanout connection and when inactive serving to vent said connection; two impulse valves each adapted to deliver a timed pressure impulse in response to the development of pressure thereupon; a pair of vent chokes; connections including a double-seated check valve for directing impulses from whichever impulse valve is active to the motor of said cleanout relay and for connecting a corresponding one of said vent chokes with such motor; and a sanding control valve having a sanding position in which it develops pressure in the motor of the sanding relay and develops pressure upon one of said impulse valves, and a running position in which it vents said motor and develops pressure on the other of said impulse valves.

20 5. A control valve mechanism for use with sanding traps of the type having a sanding air connection and a cleanout air connection, said mechanism comprising in combination, pressure operated means for supplying sanding air to the sanding connection; a second pressure operated means for supplying cleanout air to the cleanout connection; two distinct impulse valves each arranged, upon the supply of air under pressure thereto, to deliver a fluid pressure impulse to said second pressure operated means; and a sanding control valve having a sanding position in which it supplies air under pressure to the first named pressure operated means, and to one of said impulse valves; and a running position in which it vents said first named pressure operated means and supplies air under pressure to the other of said impulse valves.

HENRY NORTON SUDDUTH.
